UNITED STATES PATENT OFFICE.

FRANCIS EDWARD ELMORE, OF LONDON, ENGLAND.

PROCESS FOR SEPARATING FINELY-DIVIDED MATERIAL.

No. 826,411.

Specification of Letters Patent.

Patented July 17, 1906.

Application filed July 10, 1905. Serial No. 269,127.

To all whom it may concern:

Be it known that I, FRANCIS EDWARD ELMORE, electrometallurgist, a subject of the King of Great Britain, residing at 4 Broad Street Place, in the city of London, England, have invented a certain new and useful Process for Separating Finely-Divided Material by Causing it to Rise or Float in a Liquid, of which the following is a specification.

Processes of separation have been devised which depend upon the circumstances that under certain conditions some of the particles of a finely-divided mixture rise or float in a liquid, while others sink therein. Among artificial conditions for bringing about such a separation is mixing a pulp of the finely-divided material with an immiscible liquid, such as tar or oil, with soap or the like, or with an alkali, an acid, air, or a gas, or with any of the aforesaid substances in conjunction with each other.

In the specification of my British Patent No. 13,578 of 1904 I have described subjection of the liquid to the action of an electric current as one method of attaining the desired flotation of certain particles.

By the present invention all such processes are improved, more particularly in the respect that a smaller proportion of the added substance, such as oil or acid, may be used, by conducting them wholly or in part under a reduced pressure. For instance, a vacuum or partial vacuum may be maintained in the separating vessel or chamber.

The invention does not include any particular form of apparatus, but the accompanying drawing illustrates in vertical section a suitable form.

a is a vat (constructed of a suitable material to withstand any chemical action of the contained liquid) whose conical cover b rests on a washer c, supported by the flange d on the vat. The summit of the cone is perforated and has a flange e, which forms a circular channel f around the summit, wherefrom is an escape-pipe g, dipping at its lower end into the vat h. A shoulder on the flange e receives a washer i, on which rests a bell k, preferably of glass.

At the bottom of the vat a is a circumferential channel l, having an escape-pipe m, the lower end of which dips into a vat n. Through a stuffing-box o at the center of the bottom passes a shaft p, carrying a pulley r and a rake of suitable material s, which is revolved

by the pulley in any suitable manner. The teeth of this rake extend to within a short distance of the bottom of the vat, with the exception of the two end teeth, which extend to within a short distance of the bottom of the circumferential channel l. The pipe t, the lower end of which dips into a vat u, delivers pulp above the rake at a greater rate than the escape-pipe m can carry it away, so that a part of the liquid escapes through the summit of the cone into the channel f and away by the pipe g. The cover k is fitted with a baffle-plate x to prevent splashes being carried into the pipe v, which is connected to an exhauster or air-pump. If the vats h and n be filled with water and the vat u be filled with the pulp to be treated together with the separating medium and a suction be applied through pipe v, the vat a will be filled from vat u, the relative heights of the vats h, n, u, and a having been properly adjusted to secure this. The pipes g, m, and t may be fitted with cocks or valves for regulating the flow or the lengths of the respective pipes may be made adjustable.

By means of the air-pump or exhauster a suitable minus pressure is maintained in the vat a, and a continuous passage through vat a of material to be treated is secured by proper regulation. As the particles to be separated pass through vat a some of them settle on the bottom and are transferred by rake s to trough l and thence by pipe m to vat n. Other of the particles ascend in vat a and pass away with more or less of the liquid through the perforation in the summit of the conical cover b, thence to the channel f, and by pipe g to vat h.

I claim—

A process of separating certain constituents of finely-divided material consisting in mixing the material with a liquid and a substance that has a selective affinity for some of the constituents, subjecting the mixture to a pressure below that of the atmosphere and collecting the particles floated, substantially as described.

In testimony whereof I have signed my name to this specification in the presence of two subscribing witnesses.

FRANCIS EDWARD ELMORE.
